UNITED STATES PATENT OFFICE.

JOHN W. ANDERSON, OF SOUTH BEND, INDIANA.

SPRINKLING-NOZZLE.

SPECIFICATION forming part of Letters Patent No. 396,059, dated January 15, 1889.

Application filed August 23, 1887. Serial No. 247,686. (No model.)

To all whom it may concern:

Be it known that I, JOHN W. ANDERSON, a citizen of the United States, residing at South Bend, in the county of St. Joseph and State of Indiana, have invented a new and useful 5 Sprinkling-Nozzle, of which the following is a specification.

My invention relates to improvements in that class of sprinkling-nozzles in which the 10 water is discharged through a slotted opening; and the objects of my invention are, first, to construct a sprinkling-nozzle suitable for attaching to street-sprinkling tanks, so that the water will leave the nozzle in a solid 15 sheet or jet and spread sufficiently to form a spray before it reaches the ground; second, to afford facilities for increasing and diminishing the size of the opening through which the water issues, and, third, to provide a supplementary jet from the same head. I attain 20 these objects by the mechanism illustrated in the accompanying drawings, in which—

Figure 1 is a vertical section of the entire machine, and Fig. 2 is a top view at the line

25 A B.

Similar figures refer to similar parts throughout the several views.

4 is the body of the nozzle, preferably of circular form, but may be in straight lines 30 without departing from the spirit of my invention. At the bottom of the shell of the nozzle 4 is an upwardly-inclined flange, 5, which extends about half-way around the circle when constructed in circular 35 form, and is set at the proper angle to give the stream the required spread. The flange 5 also projects inward beyond the metal forming the lower side of the slot, as shown in Fig. 1. A bottom plate, 6, has a rim, 7, which extends around the edge about the 40 same distance as the flange 5. The bottom plate, 6, may be fastened to the lower end of the shell of the nozzle 4; but I prefer making it with a semicircular flange, 8, of suitable 45 diameter to slide over the shell of the nozzle 4. A finger or flange, 9, attached to the bottom plate, runs up inside the shell of the nozzle, and in combination with the flange 8 forms a 50 guide to hold the bottom plate in position, and affords facilities for adjusting the size of

the slot between the flange 5 and rim 7. I attach a rod, 10, to the flange 8, by which, with proper connections, the driver can while in his seat enlarge or diminish the size of the slot at pleasure. Two slots can be used in 55 the same nozzle; but preferably, when the nozzle is to have two discharge-slots, I make the casing with a partition, 13, which gives a supplementary water-way, 12, the bottom being of similar shape and equivalent to the 60 bottom plate, 6. The bevel-flange 15 is of similar size and shape to the flange 5 at the bottom of the shell. The water is let into the nozzle 4 by the valve 11, which may be of any well-known form. The valve 16 admits the 65 water to the supplementary chamber 12, and the valve-stems 17 and 18 are connected to suitable rods running to foot-levers near the driver's seat. If desired, one valve may supply both nozzles. The chamber 4 is screwed 70 or bolted to any suitable reservoir or drum having an inlet through which the water is conducted from the tank.

In operation the water is admitted to the nozzle 4 through the valve 11, when it flows 75 against the rim 7 of the bottom plate, 6, then upward and strikes the flange 5, which spreads it and directs it outward, converting it into drops or spray by the time it reaches the ground. Should more water be needed, the 80 valve 16 is opened and a second stream is turned on, or the flow of the lower nozzle is increased by lowering the bottom plate, 6; or both means may be used at the same time to increase the discharge of water. 85

I have described the upward incline of the bottom end of the shell of the nozzle 4 as a bevel-flange, as that construction makes the article neater and lighter; but it is evident that the same result might be obtained by 90 making the shell of the nozzle sufficiently thick to give the length of incline required and would not depart from the spirit of my invention.

I am aware that prior to my invention 95 sprinkling-nozzles have been made with a slotted discharge; so I make no claim, broadly, to a slot; but

What I do claim as new, and desire to secure 100 by Letters Patent, is—

In a sprinkling-nozzle, a shell having two water-ways therein and having an independent discharge-slot communicating with each water-way, and an upwardly-inclined flange forming the upper side of each slot and projecting out beyond that portion of the shell which forms the lower side of the slots, in

combination with two inlet-valves located inside the body of the nozzle, substantially as shown and described.

JOHN W. ANDERSON.
